UNITED STATES PATENT OFFICE.

ROYAL CORBIN, OF CHAMPLAIN, NEW YORK.

PAPER-CLIP.

No. 899,386.

Specification of Letters Patent. Patented Sept. 22, 1908.

Application filed January 21, 1908. Serial No. 411,997.

To all whom it may concern:

Be it known that I, ROYAL CORBIN, a citizen of the United States, residing at Champlain, in the county of Clinton and State of New York, have invented new and useful 5 Improvements in Paper-Clips, of which the following is a specification.

This invention relates to paper clips, the object of the invention being to provide a simple, cheap and practical clip of unusual 10 capacity for holding together a pile of papers or leaves either at the edge thereof or at a point intermediate the ends of a pack of folded papers, in which latter event the clip 15 which is laterally expansible is adapted to clasp the opposite edges of the papers as well as obtain a firm hold on the body portions of said papers.

With the above and other objects in view, 20 the invention consists in the novel construction, combination and arrangement herein fully described, illustrated and claimed.

The accompanying drawing represents a plan view of a paper clip shaped in accordance with the present invention.

The clip contemplated in this invention is composed of a single piece of spring wire, the central portion of which is bent to form a central jaw or clasp consisting of substantially parallel branches 1 and 2 connected by a curvilinear portion 3. This forms a substantially U-shaped central jaw or clasp which is open at one end and closed at the other end. After forming the central jaw or 35 clasp, the opposite portions of the spring wire are bent laterally in opposite directions and substantially perpendicular to the branches 1 and 2 to form cross bars 4 and 5 which connect the branches 1 and 2 with oppositely arranged side bars 6 and 7, the latter being 40 formed by bending the wire substantially

at right angles to the cross bars 4 and 5. Finally the ends of the wire are bent inward to form inbent clasps 8 and 9 which are substantially perpendicular to the side bars 6 and 7, the said inbent clasps or ends terminating short of the parallel branches 1 and 2.

From the foregoing description taken in connection with the accompanying drawing it will be observed that there are no intersecting or crossing points in the entire clip. In this way an unusual degree of resiliency or spring action is imparted to the clip adapting the same as a whole to yield to an extraordinary degree and proportionately increasing the holding capacity of the clip. The clip may be applied to the edges of a batch of sheets or papers to be held thereby or when such papers are folded in the usual legal form, they may be slipped over the central 50 jaw or clasps and under the inbent lateral clasps while the opposite side bars 6 and 7 will cross the opposite folded edges of the papers which are thus securely held at a number of different points.

Having described the invention, I claim:

A clip of the class described composed of single pieces of spring wire bent to form a central open loop with substantially parallel branches, and rectangular clasps at opposite 70 sides of said loop comprising inbent terminals disposed at right angles to the loop, the closed end of the loop being extended to project outside of or beyond the plane of said terminals.

In testimony whereof I affix my signature in presence of two witnesses.

ROYAL CORBIN.
